UNITED STATES PATENT OFFICE.

JOHN CONDELL, OF NEW YORK, N. Y.

DESIGN FOR A LAST.

SPECIFICATION forming part of Design No. 19,801, dated May 6, 1890.

Application filed October 22, 1889. Serial No. 327,872. Term of patent 14 years.

To all whom it may concern:

Be it known that I, JOHN CONDELL, a citizen of the United States, residing in the city, county, and State of New York, have invented and produced a new and original Design for Lasts for Boots and Shoes, of which the following is a specification, reference being had to the accompanying drawings, forming a part thereof.

10 Figure 1 is a side elevation of a last showing my design; Fig. 2, a cross-section thereof near the toe end in line $x x$; Fig. 3, a similar section at the instep in line $y y$; Fig. 4, a similar section at the heel in line $z z$ of Fig. 15; and Fig. 5 is a bottom view of the last.

The shape of the new last A differs from that of other lasts, first, in the configuration of the heel end. In my design the heel end is rounded at the bottom so as to partake 20 very closely of the form of a segment of a sphere, and it presents substantially in outline, when viewed laterally, a regular curve $a a$, embracing more or less the quadrant of a circle, as shown in Fig. 1, and when viewed 25 endwise a nearly semicircular convex curve $b b$, as shown in Fig. 4. The curved convex outline $a a$ terminates at its upper end in a straight line $a c$, inclining inward, as shown in Fig. 1. The upper portion of the heel end 30 is contracted at its sides, presenting in outline re-entrant or concave curves $d c d c$, as shown in the cross-section, Fig. 4, so that its general form in cross-section at the heel is, in a measure, pear-shaped in outline. This 35 last A differs in its design from other lasts, secondly, in its configuration at the instep or middle portion thereof, and, thirdly, at its widest portion about midway between the instep and toe. Its peculiar configuration 40 at each of said points is illustrated clearly in the cross-section thereof shown in Figs. 3 and 2. In cross-section through the instep and arch of the foot, taken in line $y y$ of Fig. 1, the bottom or under side of the last 45 forms, as shown in Fig. 3, an outward convex curved line having its lowest point f on the outer side of the last, said line extending in an upwardly-inclined direction from the point f to a much higher point g on the 50 opposite side, these two points being defined by the apex of the angle, more or less obtuse, which appears between the bottom and sides of the last and extends from end to end thereof, presenting to the eye a well-

defined continuous line w around the same, 55 as shown in Figs. 1 and 5.

From the lowest point f on the outer side of the last, in the plane of the cross-section at $y y$, the side of the last swells outwardly, at first with a full rounded convex curve $f h$, 60 which, as it inclines inward, becomes less full and is carried to its highest point h upon an arc of very long radius. On the opposite side or inner side of the last, starting from the angle g , the side of the last swells outwardly with a well-rounded convex curve, 65 which is lengthened somewhat as it inclines inwardly to meet at h the curve $f h$, and the outline in cross-section of the central portion of the last is thus made to present a 70 general ovoidal form having the contour of its wider lower end interrupted by the intersecting curved line $f g$ of much longer radius, as is clearly shown in Fig. 3.

In its cross-section at the ball of the foot, 75 in line $x x$ of Fig. 1, the last presents in outline a slightly-rounded convex bottom line $i k$, as shown in Fig. 2, whose end at i on the outer side of the last is slightly higher than its opposite end k , an outer side line $i l m$, 80 which, extending upward, curves rather abruptly, as at $i l$, toward the center m of the upper side and is extended to and beyond the same in a long sweep $l n$, and an inner side line having a full outward curve $k n$ 85 reaching almost up to the level of the central point m before it meets the line $i m$ from the opposite side, as shown in Fig. 2.

The outward projections of the central portion of the two sides of the last are so proportioned as that they will fall wholly within straight lines or planes $r r r' r'$, drawn to touch the widest portion of the heel and front ends of the last, as is shown in Fig. 5. In this respect it differs from all other known 95 forms of lasts.

I claim as my invention—

The design for a last herein shown and described, the same presenting in its general outline the configuration illustrated in 100 Figs. 1 and 5, and in cross-section, at the ball of the foot, the instep, and the heel, the configuration shown in Figs. 2, 3, and 4, respectively.

JOHN CONDELL.
